CLAIM

The ornamental design for a combination of a stand and an assembly connected thereto of an xy-coupling supporting a carrier arm holding a housing containing one or two microscope bodies equipped with oculars, as shown and described.

DESCRIPTION

FIG. 1 is a right side elevation view of our new design of a combination of a stand and an assembly connected thereto of an xy-coupling supporting a carrier arm holding a housing containing one microscope body equipped with an ocular; FIG. 2 is a front side elevation view of said combination shown in FIG. 1; FIG. 3 is a left side elevation view of said combination shown in FIG. 1; FIG. 4 is a rear side elevation view of said combination shown in FIG. 1; FIG. 5 is a top plan view of said combination shown in FIG. 1; FIG. 6 is a bottom plan view of said combination shown in FIG. 1; FIG. 7 is a perspective view of said combination shown in FIG. 1; FIG. 8 is an enlarged view of the housing held by the carrier arm of said combination shown in FIGS. 1 to 7; FIG. 9 is a right side elevation view of another embodiment of our new design of the combination of a stand and an assembly connected thereto of an xy-coupling supporting a carrier arm holding a housing containing two microscope bodies equipped with two oculars; FIG. 10 is a front side elevation view of said combination shown in FIG. 9; FIG. 11 is a left side elevation view of said combination shown in FIG. 9; FIG. 12 is a rear side elevation view of said combination shown in FIG. 9; FIG. 13 is a top plan view of said combination shown in FIG. 9; FIG. 14 is a bottom plan view of said combination shown in FIG. 9; FIG. 15 is a perspective view of said combination shown in FIG. 9; and, FIG. 16 is an enlarged view of the housing held by the carrier arm of said combination shown in FIGS. 9 to 15. The broken lines form no part of the claimed design.
